(57) **CLAIM**

The ornamental design for a mobile robot, as shown and described.

DESCRIPTION

FIG. 1 is an isometric view of a mobile robot, in accordance with the present invention;

FIG. 2 is a front view of the mobile robot of FIG. 1;

FIG. 3 is a rear view of the mobile robot of FIG. 1;

FIG. 4 is a left-side view of the mobile robot of FIG. 1;

FIG. 5 is a right-side view of the mobile robot of FIG. 1;

FIG. 6 is a top view of the mobile robot of FIG. 1; and,

FIG. 7 is a bottom view of the mobile robot of FIG. 1.

In the drawings of FIGS. 1 through 7, the broken lines illustrate unclaimed portions of the mobile robot that form no part of the claimed design.

1 Claim, 6 Drawing Sheets(56)
